UNITED STATES PATENT OFFICE.

FREDERICK H. BRAHE, OF CHICAGO, ILLINOIS.

COMBINED WASH-STAND AND CHAMBER-PAIL.

SPECIFICATION forming part of Letters Patent No. 475,052, dated May 17, 1892.

Application filed September 5, 1891. Serial No. 404,801. (No model.)

To all whom it may concern:

Be it known that I, FREDERICK H. BRAHE, a citizen of the United States, residing at Chicago, in the county of Cook and State of Illinois, have invented certain new and useful Improvements in a Combined Wash-Stand and Chamber-Pail, of which the following is a specification.

This invention relates to a combined wash-stand and chamber-pail which is intended for use in the sleeping-apartments of hotels, boarding-houses, and similar buildings, so as to avoid the objectionable soiling of the floor by spilling the urine when discharging the contents of the chamber-pot into the slop-jar, and by which a wash-basin is furnished the contents of which can be discharged directly into the slop-jar after the same has been used, so that a separate wash-stand may be dispensed with.

The invention consists of a combined chamber-pail and wash-basin, which comprises a base or casing that extends around the slop-jar, said casing being open at the bottom and closed at the top, so as to act as a cover for the pail. A receiving-basin is supported above the casing by means of suitable braces or stays, a connecting-pipe between the receiving-basin and the top of the base or casing, and a wash-basin that is guided in slotted ways supported by suitable brackets on the receiving-basin, so as to be moved in forward or backward direction, and a discharge-pipe that extends from the bottom of the wash-basin into the receiving-basin, so as to be placed in line with the connecting-pipe between the basin and the top part of the casing, and permit thereby the direct discharge of the contents of the wash-basin into the slop-jar.

In the accompanying drawings, Figure 1 represents a vertical longitudinal section of my improved chamber-pail and wash-stand on line 1 1, Fig. 2. Fig. 2 is a top view of the same, parts being broken out. Fig. 3 is a vertical transverse section on line 3 3, Fig. 2.

Similar letters of reference indicate corresponding parts.

Referring to the drawings, A represents the base or casing of my improved chamber-pail and wash-stand. This casing is open at the bottom and closed at the top and made of a

height to correspond with the height of the slop-jar A', which the casing is intended to inclose.

The top of the casing A is preferably perforated, so as to ventilate the space between the slop-jar and the casing.

Above the casing A is supported by connected braces or stays C a shallow receiving-basin D, which is preferably made of enameled sheet metal or other suitable material. The bottom of the receiving-basin D is connected by a pipe D' with the top a of the casing A. The connecting-pipe D' is extended above the bottom of the receiving-basin D and recessed at one side, so that the projecting portion is of semicircular shape, said semicircular portion serving as a stop or abutment d for the discharge-pipe E' of a wash-basin E, which is guided by means of headed studs e in parallel slotted guideways e², which are supported by upwardly-extending arms E³ on the receiving-basin D. The wash-basin E may be moved in forward direction until the discharge-pipe E' abuts against the semicircular upper part of the connecting-pipe D' in backward direction as far as the slotted ways e² will permit, in which case the discharge-pipe terminates in an extension D² of the receiving-basin D, as shown clearly in Figs. 1 and 2. The parallel slotted guideways e² are connected at their rear ends by a transverse piece E⁴, which may be provided with depressions that form receptacles for the soap, tooth-brush, and the like, the entire structure being preferably enameled, japanned, nickel-plated, or otherwise finished, so as to present a neat and attractive appearance. A towel-supporting roller may be mounted and held on braces at the rear of the piece e⁴, as shown in dotted lines in Fig. 1.

The wash-basin E is provided with a plug f, that is attached by a chain f' to the wash-basin, said plug serving to close the upper end of the discharge-pipe E' when the basin is to be used. For this purpose the wash-basin is moved in a forward direction in its guideways into the position shown in dotted lines in Fig. 1. After the wash-basin has been used the plug is removed and the contents of the same discharged directly through the discharge-pipe E' and the connecting-pipe into the slop-pail. If the chamber-pot

is to be discharged into the slop-jar, the wash-basin is removed in its guideways in a backward direction so as to clear the front part of the receiving-basin D, in which position it 5 is out of the way of the wash-basin, so that its contents can be readily discharged into the receiving-basin, from which they are transferred into the slop-jar. Any drippings from the wash-basin are conveyed by the discharge-pipe into the receiving-basin and discharged from the same into the slop-jar, so that the contents of the wash-basin serve to some extent for flooding the receiving-basin and keeping the same in clean condition.

15 The structure combines the advantages of three different elements—namely, a slop-jar, which is covered by the closing-casing A, a receiving-basin for the contents of the chamber, and a wash-basin—so that the ordinary 20 wash-stand and the unsightly slop-jars placed alongside of the same are dispensed with and combine with a wash-basin in one structure.

The advantages of my improved chamber-pail and wash-stand are that it combines in a 25 neat and convenient manner the function of a wash-basin and a receiving-basin for the chamber with a slop-jar, in which latter the contents of the wash-basin and the chamber are discharged without any spilling of the 30 same, as was frequently the case heretofore. It also permits to some extent the direct use of the receiving-basin as a chamber without any spilling and injuring of the carpet and without the escape of obnoxious smells from 35 the slop-jar. The oil-cloth mat usually used below the slop-jar may be dispensed with; also a separate wash-basin.

By properly finishing the structure a very 40 ornamental and useful device for the bed-rooms of hotels and boarding-houses is furnished, which by its comparatively cheap price and durable construction forms a very attractive structure for bed-rooms generally.

Having thus described my invention, I 45 claim as new and desire to secure by Letters Patent—

1. The combination of a base or casing open at the bottom and closed at the top and adapted to inclose a slop-jar, a receiving-basin mounted stationary upon said base or 50 casing and provided with an extension, a connecting-pipe between the receiving-basin and the top of the casing, a sliding or movable wash-basin supported above the receiving-basin and adapted to slide in said extension, and a discharge-pipe extending from the bottom of the wash-basin into the receiving-basin, substantially as described.

2. The combination of a base or casing open at the bottom and closed at the top and 55 adapted to inclose a slop-jar, a receiving-basin mounted stationary upon said base or casing and provided with an extension, a connecting-pipe between the receiving-basin and top of the casing, horizontal guides extending above the receiving-basin, a wash-basin supported by and movable in said guides and in said extension, and a discharge-pipe extending from the bottom of the wash-basin into the receiving-basin, substantially 65 as described.

3. The combination of a casing extending around the slop-jar and resting by its top on the same, a receiving-basin supported above said casing and provided with an extension, 75 a connecting-pipe between the bottom of the basin and the top of the casing, a semicircular upward extension or abutment which serves as a stop for the sliding basin, a wash-basin supported above the receiving-basin 80 and adapted to be moved in forward or backward direction in said extension, and a discharge-pipe extending from the bottom of the wash-basin into the receiving-basin, substantially as set forth.

In testimony that I claim the foregoing as my invention I have signed my name in presence of two subscribing witnesses.

FREDERICK H. BRAHE.
